UNITED STATES PATENT OFFICE

CHARLES H. KIRBY, OF FLINT, MICHIGAN, ASSIGNOR TO MARVEL CARBURETER COMPANY, OF FLINT, MICHIGAN, A CORPORATION OF ILLINOIS

CARBURETOR

Application filed August 6, 1928. Serial No. 297,696.

This invention relates to improvements in carburetors of the type in which an auxiliary jet or nozzle constantly supplies fuel to the mixture passageway in varying quantities, 5 during the running of the engine with which the carburetor is associated.

In my copending application, filed Aug. 6, 1928, Serial No. 297,695, I have disclosed a novel carburetor provided with an auxiliary fuel discharge port above the throttle, the discharge of the fuel at this point being variable with relation to the position of the throttle, but such fuel discharge continuing during all positions of the throttle, and mingling with the fuel fed by a main nozzle. The construction is such that the auxiliary feed diminishes as the feed from the main nozzle increases, the auxiliary feed being modified in its extent by a slightly sub-atmospheric pressure in a chamber communicating with the auxiliary fuel passageway. This sub-atmospheric pressure is brought about by positioning an opening in the entering lip of the Venturi tube of the carburetor, and putting this opening in communication with said chamber; the degree of the sub-atmospheric pressure being greater as the velocity of the air entering the Venturi tube is increased.

30 In the structure disclosed in said application, instant acceleration is obtained by a U-tube, which is also controlled to some extent, by the sub-atmospheric pressure above mentioned, so that the higher the speed of the motor, the less the additional discharge for acceleration purposes.

Said application also shows a well for augmenting the U-tube supply during acceleration, and the primary object of the present invention is to provide in such a carburetor, additional means for the purpose of intermediately prolonging the accelerating charge to fill the hiatus between the emptying of the reserve leg of the U-tube, and the beginning of operations from the well. This result is brought about by a concentric annular chamber, arranged around the reserve leg of the U-tube, and this chamber is provided with a small orifice to permit air to enter the chamber slowly, and in this way,

the fuel therein will be held back temporarily, and subsequently follow up the fuel after it leaves the reserve leg, and the rate of the discharge will be dependent on the size of said orifice and the position of the 55 hole in the Venturi tube.

Another object of the present invention is to combine in a carburetor, a U-tube functioning to instantaneously supply an accelerating charge when needed; a well to furnish 60 an auxiliary accelerating charge, and an annular chamber to furnish accelerating fuel during the interim between the feed from the reserve leg of the U-tube and said well.

Another object of the invention is to provide accelerating fuel supply means of the above mentioned character, combined with a passageway opening into the entrance lip of the Venturi tube, whereby the air travelling through the Venturi tube will modify 70 the accelerating feed from the reserve leg, annular chamber and well.

The invention will now be described in detail, in connection with the accompanying drawings, in which,

Fig. 1 is a vertical sectional view, partly in elevation, of a form of the invention designed more especially with a view of clearly illustrating the invention, and showing the throttle valve closed.

Figs. 2, 3 and 4 are similar views with certain parts omitted, and illustrating the varying fuel levels in the reserve leg, annular chamber and well, as the throttle is moved from closed to open position during acceleration.

Fig. 5 is a transverse sectional view of a portion of a commercial embodiment.

Fig. 6 is a similar view of another commercial embodiment, and illustrating a modification of the main fuel control valve.

In the embodiment of the invention illustrated in Figs. 1 to 4 inclusive, 1 designates a float chamber to which the liquid fuel is fed by a pipe 2. A float 3 in the chamber, operates a valve 4 in the ordinary manner to control the feeding of the fuel from the pipe into the chamber.

As set forth in my above mentioned copending application, fuel from the chamber

1, while the engine is running, is continuously fed through a tube 5, and orifice member 6, to a chamber 7, from which it passes through a duct 8 that discharges into the 5 main mixture passageway 9 of the carburetor, above the pivoted throttle valve 10. This feed varies, due to the fact that the chamber 11, containing the tube 5, communicates with an aperture 12 in the entrance lip of a Venturi tube or throat 13, by means of ports 14, 10 15 and 16, and compartments 17 and 18.

It will be readily appreciated by those skilled in the art, that the suction exerted at 12, will vary when the throttle valve is 15 in different positions. When the throttle is in the position shown in Fig. 1, the suction in 12 will be at a minimum, and the feed through 8 will be at a maximum. On the other hand, when the throttle is fully opened, 20 as shown in Fig. 4, the suction in 12 will be at a maximum, and consequently, subatmospheric pressure through 14—18, will be communicated to the chamber 11, so that the feed through 8 will be at a minimum. Consequently, movements of the throttle will function to vary the feed through 8, such feed 25 gradually diminishing as the throttle is moved from closed to open position.

In the copending application, I have also 30 disclosed a U-tube structure, consisting of a horizontal passageway 19, a main leg 20, and a reserve leg 21. The main leg forms the main nozzle of the carburetor, and its discharge end 22 terminates within the restricted portion of the Venturi throat. The reserve leg 21 is adapted, when the motor is not running, to fill up to the level 23 with fuel, so that when the motor is started, the fuel from this reserve leg will be immediately withdrawn, as shown in Fig. 2, to furnish a rich starting mixture. The air enters the mixture 40 passageway through its inlet end 24.

The fuel is fed from the chamber 1 to the 45 passageway 19, through a conduit 25, in which orifice members 26, and 27 are interposed, and a needle valve 28 is employed to regulate the passage of fuel through the orifice member 27. A well 29 is located in the chamber 17, and communicates with the conduit 25 by a port 30, and when the engine is 50 not running, the fuel from the chamber 1 will flow by gravity into the well, until it reaches the top 31 of the latter, which is provided with an orifice member 32.

In the compartment 18, a tube 33 is arranged around the reserve leg 21 of the U-tube to provide an annular auxiliary fuel chamber 34. A ring 35 closes the upper end of the annular chamber, and fuel enters the latter through a small port 36 which places the lower end of the annular chamber in communication with the interior of the reserve leg. A port 37 in the upper end of the reserve leg, places the top portion of the annular chamber in communication with the

air space of the reserve leg, so that suction exerted through 12, will also influence the discharge of fuel from the annular chamber through the port 36.

It may readily be seen from the drawings, 70 that the opening at the upper end of the reserve leg 21 is of larger diameter than the port 37, and that the latter is of larger diameter than the orifice in the member 32. Assuming, therefore, a given suction in the passageway 19, it will be recognized that the leg 21 will empty first, the annular chamber 34 will be emptied next, and finally the well 29 will be emptied. Of course, the emptying of these parts will be influenced by the suction exerted through 12, but as the discharge end 22 of the main nozzle is right in the restricted portion of the Venturi tube, the suction at 75 22 will always be greater than that at 12, when the throttle 10 is opened to any degree.

By viewing Figs. 2, 3 and 4 at this time, it may be seen that as the throttle is opened, the feed through 8 will gradually diminish without ceasing entirely, and that after the fuel is discharged from the reserve leg 21, it will then be discharged from the annular chamber 34, and finally from the well 29. When the throttle valve is in the position shown in Fig. 4, if the valve is kept open, 80 then the main feed will be through 25, 19 and 20, and the auxiliary feed through 8.

With regard to the commercial embodiments of the invention, it will be recognized that for the purpose of compactness and mechanical expediency, it is advisable to place the parts 21, 29 and 5 at different points around the main passageway 9, instead of all in the same vertical plane as shown in Fig. 1, and in my before mentioned copending application, I have fully disclosed such an embodiment. However, the structure shown in Fig. 5 differs from that illustrated in my copending application, owing to the addition of the annular chamber for feeding the intermediate auxiliary supply. As shown in Fig. 5, the main leg or nozzle 20a communicates with its supply passageway 19a, but said passageway extends laterally instead of longitudinally, as in Fig. 1. Furthermore, the reserve leg 21a forming part of the U-tube, is arranged to one side of the carburetor, instead of between the float chamber and the main passageway. In this embodiment, the tube 33a surrounds the reserve leg to form the annular chamber 34a, and the fuel enters and leaves the annular chamber through a port 36a, while the air enters and leaves by the port 37a. In this form of 100 the invention, 12a indicates the port in the entrance lip of the Venturi tube, which is utilized to maintain sub-atmospheric pressure in the passageway 12b. In this form of 105 the invention, the orifice member 27a corresponding with the member 27 in Fig. 1, is not used in connection with the needle valve,

110

115

120

125

130

while in Fig. 6, the needle valve 28b cooperates with the orifice member 27b. It may thus be seen that the needle valve may cooperate with either one of the orifice members 5 arranged in the main supply line between the float chamber and the main fuel nozzle.

It is believed that those skilled in the art may readily understand the invention from the foregoing description when taken in connection with the accompanying drawings, and it is apparent that the details may be altered without departing from the spirit of the invention as set forth in the claims.

What I claim and desire to secure by Letters Patent is:

1. In a carburetor, a main mixture passageway, a throttle valve for controlling the passage of the mixture through said passageway, a fuel nozzle extending into the passageway, primary and a plurality of reserve supply means for feeding fuel to the nozzle during acceleration, and means communicating with the mixture passageway for placing sub-atmospheric pressure on the primary and 25 reserve supplies to modify the feeds from the same as the throttle valve is moved.

2. In a carburetor, a mixture passageway, a throttle valve in the passageway, fuel supply means, means influenced by movements 30 of the throttle valve for feeding fuel from the supply into the passageway posterior to the throttle valve, a fuel nozzle extending into the passageway, a reserve leg for supplying auxiliary fuel to the nozzle during acceleration, means for conducting fuel from the supply to the reserve leg and nozzle, a 35 chamber for a reserve supply of fuel, and means for feeding fuel to and from said chamber through the reserve leg.

3. In a carburetor, a mixture passageway, a single fuel nozzle extending into the passageway, a throttle valve controlling the flow of mixture through the passageway, main and a plurality of reserve means for supplying auxiliary fuel to the nozzle, and means controlled by suction exerted in the 45 mixture passageway for regulating the feed of fuel from the main and reserve supplies to the nozzle.

4. In a carburetor, a mixture passageway, a single fuel nozzle extending into the passageway, a reserve fuel leg, means for supplying fuel to the reserve leg and main nozzle, an annular chamber surrounding the 55 reserve leg, means for flowing fuel from the supply to the annular chamber, means for causing fuel to flow from the annular chamber to the main nozzle, after the fuel from the reserve leg has been fed to the nozzle and means communicating with the mixture passageway for placing subatmospheric pressure on the fuel in the reserve leg and annular chamber by the velocity of air passing 60 through said mixture passageway to modify

the feeds from the same as the throttle valve is moved.

5. In a carburetor, a mixture passageway and a pair of compartments, a U-tube including a reserve leg arranged in one of said compartments, and a main nozzle extending into the mixture passageway, the other compartment forming a well, means for supplying fuel to the well and U-tube, and placing the well and U-tube in communication, an annular chamber in one of the compartments surrounding the reserve leg and adapted to contain a reserve supply of fuel, a throttle valve in the mixture passageway, and means controlled by the opening of the throttle for feeding fuel from the reserve leg, annular chamber and well, to said nozzle.

6. In a carburetor, a carbureting passage having a throttle valve therein and provided with independent means for feeding fuel into said carbureting passage above and below the throttle valve, a main supply chamber, a fuel passage leading therefrom, a U tube in communication with said supply passage including a main leg and a reserve leg, the main leg extending into said carbureting passage and forming the only means for feeding fuel into said passage below the throttle valve, a well in communication with said fuel supply passage, a reserve chamber and means for feeding fuel to and from said reserve chamber through said U tube.

7. In a carburetor having a constant level reservoir, a carbureting passage, a fuel nozzle extending into said carbureting passage, means for feeding fuel constantly from said constant level reservoir to said nozzle, means for feeding primary and auxiliary supplies of fuel to said nozzle during acceleration, means for furnishing an additional accelerating supply to said nozzle during the interim between the feeds of the primary and auxiliary supplies and a passage extending from said primary and auxiliary supplies to said carbureting passage and terminating in a port entering said passage in a reverse direction to the path of air passing therethrough for placing subatmospheric pressure on the primary and auxiliary supplies by the velocity of air passing through said carbureting passage.

8. In a carburetor having a constant level reservoir, a carbureting passage provided with a throttle valve, a venturi disposed in said carbureting passage, a fuel nozzle extending into said Venturi tube, means for furnishing a primary supply of fuel to said nozzle at the intermediate open position of said throttle valve, means for furnishing a plurality of auxiliary supplies of fuel to the nozzles during acceleration caused by the opening of the throttle valve and means for furnishing an additional charge of fuel to the main nozzle during the interim between the supply of primary and auxiliary charges

and means including a passageway communicating with the carbureting passage in a direction reverse to the travel of air passing therethrough for placing subatmospheric pressure on the primary and reserve supplies by the velocity of air passing through said passageway to modify the feeds from the same as the throttle valve is moved.

9. In a carburetor having a constant level reservoir, a carbureting passage having a throttle valve for controlling the passage of explosive mixture therethrough, a nozzle supplied constantly with fuel from said constant level reservoir, means for normally metering the supply of fuel to said nozzle, a plurality of auxiliary reservoirs for successively supplying fuel to said nozzle and means for controlling the supply of fuel delivered to said nozzle from said plurality of auxiliary reservoirs by the velocity of air passing through said carbureting passage.

In testimony whereof I hereunto affix my signature.

CHARLES H. KIRBY.
